LOCOMOTIVE STOKER

Washington T. Capps, Baltimore, Md., assignor to
The Standard Stoker Company, Inc., a corpora-
tion of Delaware

Application June 29, 1934, Serial No. 733,142

2 Claims. (Cl. 198—15)

This invention relates to mechanical stokers for locomotives and particularly to stokers of that type shown in my prior application, Serial No. 634,074, filed September 20, 1932, wherein 5 coal or like solid fuel is conducted from a fuel bunker on the tender to the firing opening of the locomotive by means of telescopic and jointed feeding means allowing relative movements between the elements of the feeding means on the 10 locomotive and tender to compensate for relative movements of the locomotive and tender in the travel thereof. In the structure disclosed in my aforesaid application, Serial No. 634,074, the stoker comprises a conveyor unit mounted on 15 and receiving coal from the coal bunker on the tender, an elevator unit mounted on the locomotive and cooperating with a distributor for delivering the coal into the locomotive firebox through the firing opening, an intermediate or 20 transfer unit flexibly coupled to the conveyor and elevating units for the transfer of the coal from the one to the other, screw conveyors forming part of said units, and gearing for driving the screw conveyors. The present invention is di- 25 rected to improvements upon the construction of stoker disclosed in said application and others of its general type.

The primary object of the invention is to provide a novel construction and arrangement of 30 the stoker units for securing simplicity and economy of construction and a proper supply of coal to the locomotive in the event that the conveyor unit should become inoperative from any cause.

Another object of the invention is to provide 35 means, in the event that the conveyor unit should become inoperative from any cause, whereby the conveyor screw in the conveyor unit may be disconnected from the driving means and the latter 40 employed to drive the screw conveyors in the transfer and elevator units for the delivery of coal manually supplied to the elevator unit, whereby the operation of high speed trains on 45 schedule may be maintained, thus preventing the serious delays which occur under such conditions with other stokers and the loss of revenue occurring in the operation of de luxe trains when the conveyor mechanism in the tender is rendered inoperative by obstructions or other causes.

Still another object of the invention is to provide 50 a novel construction and arrangement of the several units whereby the conveyor unit is disposed at one side of the center line of the locomotive and tender to afford greater space for the convenience of the fireman in shoveling coal

into the elevator unit on the stoppage of the feed screw in the conveyor unit or when hand feeding is necessary to augment the power feed, and whereby the transfer and elevator units are disposed in the center line of the locomotive and 5 tender, or approximately so, so that a direct feed of fuel from the conveyor unit to the distributor may be obtained, allowing a simplified construction of parts to be employed which will operate with less wear and tear and at the same 10 time provide for a more efficient stoking action.

A still further object of the invention is to provide means to enable coal to be fed by hand directly from the tender to the stoker conduit and to permit access to the transfer and delivery 15 units for greater convenience in cleaning or unclogging the same, when clogging occurs, or inspecting or repairing the enclosed parts thereof.

A still further object of the invention is to provide a novel manner of connecting the conduits 20 of the transfer and delivery units to permit relative movements thereof while securing adequate support for said conduits.

A still further object of this invention is to provide a novel articulated transfer unit which 25 is in such relation with associate parts of the stoker mechanism that a balanced arrangement of such parts is attained.

A still further object of the invention is to provide a mechanical stoker which is simple of 30 construction, reliable and efficient in action, capable of being installed, manufactured and operated at a comparatively low cost, and which, in addition to the other desirable advantages set forth, may be conveniently and economically 35 cleaned and kept in repair.

With these and other objects in view, the invention consists of the features of construction, combination and arrangement of parts, herein- 40 after fully described and claimed, reference being had to the accompanying drawings, in which:—

Fig. 1 is a plan view with parts shown in section of a stoker embodying my invention, showing the same in operative relation to a locomotive 45 tender, parts of which are shown.

Fig. 2 is a side elevation of the stoker with parts shown in section.

Fig. 3 is a front elevation of the gearing with the gear box removed and its cover shown in 50 elevation.

Fig. 4 is a horizontal section through the gear box or casing showing the clutch in engaging position to drive all three screw conveyors.

Fig. 5 is a view similar to Fig. 4 showing the 55

clutch disengaged to throw the screw conveyor of the conveyor unit out of action while maintaining the other screw conveyors in gear for a driving action thereof.

5 Fig. 6 is a section taken substantially on line 6-6 of Fig. 1.

Fig. 7 is a section on line 7-7 of Fig. 6.

Referring now more particularly to Figs. 1 to 5, inclusive, of the drawings, 1 designates a portion 10 of the locomotive frame, 2 the cab deck, 3 the backhead, 4 the firing opening, and 5 a portion of the rear cab wall of a locomotive, and 6 designates a portion of the tender structure, 6a a portion of the front wall thereof, and 7 the tail 15 or slope sheet of the coal bunker thereof, while A designates the stoker as a whole, which comprises a conveyor or feed unit A' on the tender, an elevator or delivery unit A² on the locomotive, and a transmission or transfer connection or unit 20 A³ between such conveyor and elevator units.

The conveyor unit A' on the tender comprises a fixed trough-shaped conduit 8 arranged beneath the shovel sheet or floor A⁴ of the fuel bunker or coal bin of the tender and in communication therewith through a longitudinally extending slot or opening A⁵ in said floor. In this conduit or trough 8 is arranged a helical conveyor screw 9 which feeds the fuel forward to the transfer unit A³, from which it is delivered to 25 the elevator unit A². In practice, the fuel discharge slot or opening A⁵ in the floor A⁴ is provided with adjustable cover plates or slides, which may be opened or closed at any point desired 30 along the length of the opening to regulate the discharge of fuel.

The trough 8 is arranged mainly at one side of the longitudinal center of the deck or floor A⁴ in order that a comparatively wide space or platform portion A⁶ may be provided at the opposite side of the longitudinal center of the floor to afford greater room and convenience for the use 40 of the fireman in shoveling coal for emergency manual stoking operations and to place the parts of the stoker conveyor mechanism in proper operating alignment. The elevator or delivery unit A², which comprises a conduit 10 having a conveyor screw 11 disposed therein, is, on the other hand, arranged in the vertical plane of the longitudinal center or axis of the locomotive, so that 45 the longitudinal axes of the units A' and A² lie in different vertical planes, one displaced laterally to one side of a central vertical plane bisecting the locomotive and tender and the other axially coincident with such vertical plane.

50 The transfer unit A³, which comprises a conduit 12 having a conveyor screw 13 disposed therein, extends at an angle to the bisecting vertical plane between the units A' and A² and is provided at its rear end with an offset portion 55 14 communicating with the side of the conveyor facing the bisecting vertical plane and formed at its rear end with an entrance-way and coupling member or connection 15 receiving a tubular projection 16 forming a fuel outlet and coupling member or connection at the forward end of 60 the trough or conduit 8. The arrangement is thus such that the fuel fed forward from the conduit 8 by the conveyor screw 9 passes into the offset inlet 14 at the rear end of the intermediate conduit 12 from which it is conveyed 65 forwardly by the feed screw 13.

The projection or coupling member 16, as shown particularly in Figs. 6 and 7, has an outer spherical surface arranged to fit within the bushing sleeve or ring 16a disposed between the same

and the coupling member 15, the inner surface of said bushing sleeve or ring being of spherical shape and articulately fitting over the complementary shaped spherical surface of the member 16. The outer surface of the bushing sleeve 5 16a is cylindrical in shape and fits within the cylindrical formation at the rear of the coupling member 15. Thus, the parts 16, 16a form a ball and socket connection between the conduits, and the parts 16a, 15 form a sliding joint therebetween whereby a combined sliding and articulating joint connection is furnished at this point to adapt the stoker conduits as a whole to have relative backward and forward sliding movements and the conduits 8 and 12 to have relative vertical and lateral articulating movements to compensate for such movements between the locomotive and tender. In order to permit ready and convenient assemblage and disassembly of the parts 15, 16a and 16, the member 15 is formed 10 in two halves or sections 15a and 15b, one of which is cast integral with the conduit 12 and the other formed as a separate removable part, said parts being flanged, as at 15c for passage 15 of connecting bolts 15d, whereby the parts are adapted to be assembled and disassembled in an obvious manner. The bisecting line between these sections is preferably so placed, as clearly shown in Fig. 6, as to permit ready application 20 and removal of the removable parts 15b without interference from parts of the tender or other parts of the stoker.

The intermediate conduit 12 is provided at its forward end with a spherical coupling portion 17 which fits within a spherical socket 18 at the lower end of the elevator conduit 10, so that an articulating joint is provided at this point in the stoker line, the portions 15-16 and 17-18 thus providing joints between the stoker conduits 8, 12, and 10 to adapt the same to have free relative longitudinal and universal lateral movements to compensate for all relative movements between the locomotive and tender in service. It will be observed that the transfer unit A³ is so arranged 30 that the greater portion thereof is at one side 40 of its axis of articulation. This axis is a line joining the centers of the two ball joints.

The body portion of the elevator conduit 10 extends upwardly and forwardly at a suitable angle of inclination from its lower or inlet end 50 through the cab deck and carries at its upper or discharge end a distributor A⁷ of the construction hereinafter described, whereby the fuel delivered by the conveyor 11 is discharged through the firing opened into the firebox of the locomotive. 55 The lower end of the conduit 10 is suitably supported from and flexibly or slidably connected to the locomotive frame, as shown at 19, and is also rigidly connected to the back sheet by suitable ties or braces 20. At its upper end the conduit 10 is provided with a flanged head or enlargement 21 which is attached at the point 19a to a flanged ring or flanged bracket members 22 fastened to the backhead. In addition to the coupling and supporting connections for the elevator 60 unit A² above described, the transfer unit A³ may be partially supported from a portion 23a of the tender frame by a sliding connection, as at 23, to relieve the joint 15-16 of a part of its weight 65 while allowing back and forth compensating movement of said conduit as previously described. Wear plates 22a, bolted or riveted to the head of the conduit 10, may be provided to protect the side walls of the firing opening from undue wear and abrasion. The construction of the connec- 70 75

tions between the members 15-16 and 17-18 may further be such as to adapt the members of either connection or both to readily separate when the locomotive and tender are uncoupled 5 and moved apart to facilitate the disconnection of the transfer unit from its cooperating units on the locomotive and tender.

The screw conveyor 9 is not in driving connection at its forward end with the rear end of 10 the screw conveyor 13, but is driven from the same source of power. The screw conveyor 13, on the other hand, is coupled by a universal joint 24 to the rear end of the screw conveyor 11 and therefore transmits driving motion thereto, the 15 arrangement being such that the coal fed from the conduit 8 by the conveyor 9 passes through the offset inlet 14 from the conduit 8 into the conduit 12 and is continuously fed forward to the distributor through the conduits 12 and 10 by 20 the action of the conveyor screws 13 and 11. The mechanism for driving the screw conveyors comprises a driving motor 25 which transmits motion to a primary or drive shaft 26 which transmits the driving power to drive gearing arranged in 25 a gear box or casing 27 arranged at the rear end of the trough or conduit 8. The shaft 26 may be of telescopic type and connected by universal or other flexible joints to the engine and primary drive element of the gearing so that it may have 30 the necessary expanding, contracting and flexing motions under running conditions of the tender. The gearing enclosed in the gear box comprises a primary shaft 28 driven by the driving shaft 26, a shaft 29 for driving the screw conveyor 9, 35 a shaft 30 universally jointed to a shaft 31, extending alongside the trough 8 and universally jointed to the conveyor 13, for driving the conveyors 13 and 11, a longitudinally sliding clutch shaft 32 provided with a clutch member 32' to 40 engage a clutch member 29' on the shaft 29 and normally held in clutch engaging position by a spring 33, a transmission shaft 34, intermeshing gears 35 and 35' on the shafts 28 and 34, intermeshing gears 36 and 36' on the shafts 34 and 45 32, and intermeshing gears 37 and 37' on the shafts 32 and 30, the arrangement being such that when shaft 32 is in clutch engagement with the shaft 29 motion will be transmitted from the 50 motor drive shaft for driving both shafts 29 and 30 simultaneously, whereby feed motion will be transmitted to all screw conveyors, while when shaft 32 is moved rearwardly to disengage the clutch shaft 29 will be operatively disconnected therefrom and the screw conveyor 9 will not be 55 driven, but the gears will maintain a meshing engagement for the driving of the shaft 30 and the screw conveyors in the transfer and elevating the conveyors driven thereby. Thus it will be understood that in the event of the clogging or 60 disengagement of the conveyor unit A', whereby the feed of coal therethrough by the conveyor 9 is arrested, the gearing may be disengaged from driving connection with said conveyor and the conveyors in the transfer and elevating units A' 65 and A² operated to feed coal therethrough to the firebox, in which operation the coal from the source of supply on the tender may be manually supplied to the working units of the stoker. In practice the ratio of the gearing in the gear box 70 is preferably such that in the case of a two-cylinder double-acting motor of approximately 500 R. P. M. the conveyor screws 11 and 13 will be driven at a rate of speed from fifteen to twenty-five percent faster than the screw 9, the 75 increased rate of speed of the conveyors 11 and 13

with respect to that of the other conveyor 9, adapting them to be used for emergency purposes to deliver with the amount of coal being fed up by the conveyor 9 an additional amount shoveled in to the elevator conduit by the fireman. This is of advantage, also, where the coal contains a high percentage of large lumps and sufficient coal can not be handled by the conveyor 9, in which case the fireman may overcome the difficulty by shoveling sufficient coal to make up 10 that required to feed the locomotive.

In order to allow hand stoking to be readily carried out when necessary the lower end of the elevator conduit is provided with an expanded, hopper-like portion 38 normally closed by a 15 hinged cover 39, the mouth or inlet of which hopper is arranged above the cab deck so that the fireman can have convenient access thereto. The rear end of the transfer mechanism may also be provided with an opening 40 normally closed 20 by a detachable cover plate 41 which may be opened to permit access to its inlet end.

It often occurs on locomotives in passenger service, which are coaled with a high percentage of large lump coal, that in coaling the locomotive 25 tender a large proportion of the lump coal clogs at the coal gates and at the forward end of the conveyor trough 8, making it at times very difficult to obtain the feed of a sufficient amount of coal for consumption through the conveyor system. My invention overcomes this difficulty, as it allows manual stoking to be used in conjunction with automatic stoking, and in a very simple manner convenient to the fireman, and provides 30 a mechanical stoker of great flexibility to suit varying conditions of service, since, in the event of deficient feeding, or of maximum stoking being required, the amount of coal supplied to the firebox may be augmented by hand action, while, even in the event of the conveyor 9 becoming 35 broken or inoperative, the conveyors 11 and 13 may be employed in conjunction with hand feeding to furnish an ample supply of fuel to the locomotive. This is of very great advantage 40 especially in connection with passenger locomotives, where delays must be reduced to the minimum.

In practice the gearing in the gear box or casing 27 is preferably enclosed in an air-tight manner, and all those bearings which tend to allow 50 leakage are suitably packed or sealed or in the form of blind bushings or glands, so that a store of lubricant may be kept in the gear case. For the purpose of keeping this lubricant in a suitable fluid state in cold weather, a pipe connection 42 may be supplied for conducting exhaust steam from the locomotive boiler to a chamber 43 which is formed in the cover 27a of the gear casing 27. I may employ in practice any suitable 55 means for operating the clutch shaft to throw the feed screw 9 into and out of action, that shown in the present instance comprising a shift lever 43 connected to the outer end of the shaft 32 and coupled by a connecting rod 44 with an operating hand lever or other suitable operating device 44' mounted at or near the front end of the tender so that the clutch shaft may be readily and conveniently operated by the fireman.

From the foregoing description, taken in connection with the drawings, the construction and operation of my improved stoker will be readily understood by those versed in the art, and its advantages appreciated without an extended, further and detailed description. Suffice it to say that this improved construction of stoker 75

- makes it possible to operate high speed trains on schedule by hand stoking through the opening in the conduit 12, even in the event of derangement of the conveyor mechanism in the tender, where 5 it most commonly occurs, so as to avoid serious delays and possible loss of revenue on de luxe trains; as well as to ensure the supplying of an adequate amount of fuel under such conditions to the firebox to maintain a proper working steam 10 pressure in the locomotive under all other service conditions. The construction of the stoker itself also generally simplifies and improves the construction of the stoker mechanism so as to secure simplicity and economy of construction, maintenance, coal consumption, and reduction of smoke 15 and a more flexible performance when difficulty arises through the primary conveyor being rendered inoperative, due to clogs, broken screws, etc., which would render other existing types of 20 stokers useless. Practical use has shown that the stoker may be manually fired through the opening 39 in the elevator casing without loss of time or material reduction in the steam gage or boiler pressure. 25 While the structure disclosed for purposes of exemplification is preferred, it will, of course, be understood that changes in the form, construction and arrangement of parts within the scope of the appended claims may be made without departing from the spirit or sacrificing any of the 30 advantages of the invention.
- It is to be noted that the improved drive mechanism, the fuel distributor and the flexible coupling of the embodiment of my invention originally described and disclosed herein have been made the subject matter of divisional applications Serial No. 117,122, Serial No. 117,123, and Serial No. 117,124, respectively, all filed on the 22nd day of December, 1936.
- 40 What I claim is:—
1. In an intercoupled locomotive and tender, a stoker for transferring fuel from the tender to

the locomotive comprising a conduit on the locomotive, a conduit on the tender, a transfer conduit between the first and second named conduits, said transfer conduit at one end being flexibly related with one of said conduits, the opposite end of said transfer conduit being provided with an elbow disposed at one side of the major portion of said transfer conduit, said elbow being flexibly related with the other of said conduits whereby the transfer conduit articulates when relative movement between said intercoupled vehicles occurs, the axis of articulation of said transfer conduit being disposed in a vertical plane passing through the aforesaid ends of said transfer conduit, the major portion of said transfer conduit being at one side of such vertical plane, and means for restraining downward swinging movement of the major portion of said transfer conduit about its axis of articulation. 5

2. In an intercoupled locomotive and tender, a 10 stoker for transferring fuel from the tender to the locomotive comprising a conduit on the locomotive, a conduit on the tender, a transfer conduit between the first and second named conduits, said transfer conduit at one end being flexibly related with the first named conduit, the opposite end of said transfer conduit being provided with a fuel inlet elbow disposed at one side of the major portion of said transfer conduit, said elbow being flexibly related with the second 15 named conduit whereby the transfer conduit articulates when relative movement between said intercoupled vehicles occurs, the axis of articulation of said transfer conduit being disposed in a vertical plane passing through the aforesaid ends of said transfer conduit, the major portion of said transfer conduit being at one side of such vertical plane, and means for restraining downward movement of the major portion of said transfer conduit about its axis of articulation. 20
